[57] CLAIM

The ornamental design for a front face of a panel for a vending machine, as shown and described.

DESCRIPTION

FIG. 1 is a front perspective view of a front face of a panel for a vending machine showing my new design;

FIG. 2 is a front elevational view thereof;
FIG. 3 is a second modified embodiment of the form shown in FIG. 2;
FIG. 4 is a third modified embodiment of the form shown in FIG. 2;
FIG. 5 is a fourth modified embodiment of the form shown in FIG. 2;
FIG. 6 is a fifth modified embodiment of the form shown in FIG. 2;
FIG. 7 is a sixth modified embodiment of the form shown in FIG. 2;
FIG. 8 is a seventh modified embodiment of the form shown in FIG. 2;
FIG. 9 is the eighth modified embodiment of the form shown in FIG. 2;
FIG. 10 is the ninth modified embodiment of the form shown in FIG. 2;
FIG. 11 is the tenth modified embodiment of the form shown in FIG. 2;
FIG. 12 is the eleventh modified embodiment of the form shown in FIG. 2;
FIG. 13 is the twelfth modified embodiment of the form shown in FIG. 2;
FIG. 14 is the thirteenth modified embodiment of the form shown in FIG. 2;
FIG. 15 is the fourteenth modified embodiment of the form shown in FIG. 2;
FIG. 16 is the fifteenth modified embodiment of the form shown in FIG. 2;
FIG. 17 is the sixteenth modified embodiment of the form shown in FIG. 2;
FIG. 18 is the seventeenth modified embodiment of the form shown in FIG. 2; and,
FIG. 19 is the eighteenth modified embodiment of the form shown in FIG. 2.
